CLAIM

The ornamental design for a portion of a display screen with transitional icon, as shown and described.

DESCRIPTION

FIG. 1 is a front view of the first image in the sequence for a portion of a display screen with transitional icon showing the new design;

FIG. 2 is a front view of the second image thereof;

FIG. 3 is a front of the third image thereof;

FIG. 4 is a front view of the fourth image thereof;

FIG. 5 is a front view of the fifth image thereof; and,

FIG. 6 is a front view of the sixth image thereof.

The appearance of the transitional image sequentially transitions between the images shown in FIGS. 1-6. The process or period in which one image transitions to another forms no part of the claimed design.

The one-dot chain line showing of portions of a display screen is for the purpose of illustrating environmental structure and forms no part of the claimed design.
